UNITED STATES PATENT OFFICE.

ISIDORE BUCHMAN, OF BROOKLYN, NEW YORK, ASSIGNOR TO THE I. BUCHMAN CO., INC., OF BROOKLYN, NEW YORK, A CORPORATION OF NEW YORK.

PILLOW OR CUSHION.

Application filed March 5, 1925. Serial No. 13,404.

Where clothespins have been used for fastening pillows or cushions to clotheslines for airing purposes, it has been extremely difficult to properly secure the pillows or 5 cushions to the clotheslines against danger of becoming detached therefrom.

The object of my invention is to provide the pillow or cushion with novel, simple and effective means for obviating this danger; 10 said pillow or cushion being bifurcated to form flaps arranged to receive the clothesline between them; means such as coacting fastening elements being provided for detachably securing the flaps together around 15 the clothesline.

Practical embodiments of my invention are represented in the accompanying drawings, in which

Fig. 1 represents a detail front elevation 20 showing the pillow or cushion bifurcated at one corner thereof and suspended from a clothesline.

Fig. 2 represents a detail front elevation of the same on a larger scale.

Fig. 3 represents a detail front elevation 25 with the flaps opened to release the pillow from the clothesline.

Fig. 4 represents a detail section taken in the plane of the line IV—IV of Fig. 2, 30 looking in the direction of the arrows.

Fig. 5 represents a detail front elevation with the flaps open, showing a modified form of fastening for the flaps.

Fig. 6 represents a front elevation showing 35 a pillow or cushion suspended from a clothesline, the pillow or cushion being bifurcated along one end thereof to form the flaps.

Fig. 7 represents an edge view of the 40 same.

Fig. 8 represents a detail cross section showing a modified form in which the flaps are unlined.

The clothesline is denoted by 1 and the 45 pillow or cushion by 2, which pillow or cushion may be of any desired shape, size and character.

In the form shown in Figs. 1 to 4 inclusive, the pillow or cushion is bifurcated at 50 one corner thereof and provided with a lining 3, to form hollow flaps 4 and 5 having their interiors open to the interior of the pillow or cushion. When it is desired to suspend the pillow or cushion these two 55 corner flaps 4 and 5 are opened sufficiently

to receive the clothesline between them and means are provided for detachably securing the flaps together around the clothesline, such means in the form under discussion including a pair of coacting fastening elements, such as snap fasteners 6 and 7.

In the form shown in Fig. 5 the fastening elements are shown as a button 8 and its coacting buttonhole 9.

In the form shown in Figs. 6 and 7 the 65 end of the pillow or cushion is bifurcated and provided with a lining 10 to form two flaps 11 and 12 arranged when opened, to receive the clothesline between them, two pairs of coacting fastening elements, such 70 as snap fasteners 13, 14 being provided for detachably securing the flaps around the clothesline.

In Fig. 8 I have shown a form in which the front and back of the pillow are stitched 75 together, as shown at 15, to form two unlined flaps 16 and 17, the pair of coacting fastening elements in this form being denoted by 18 and 19.

From the above description it will be seen 80 that I have provided a very simple and effective means for detachably suspending the pillow or cushion from the clothesline.

It is evident that various changes may be resorted to in the construction, form 85 and arrangement of the several parts without departing from the spirit and scope of my invention; hence, I do not intend to be limited to the particular embodiments herein shown and described, but 90

What I claim is:—

1. A pillow or cushion bifurcated at one corner to form flaps arranged to receive a clothesline between them, and means for detachably securing said flaps together around 95 the clothesline to suspend the pillow or cushion therefrom.

2. A pillow or cushion bifurcated at one corner and lined to form flaps, the interiors of which are open to the interior of the 100 pillow or cushion, said flaps being arranged to receive a clothesline between them, and means for detachably securing said flaps together around the clothesline to suspend the pillow or cushion therefrom. 105

In testimony, that I claim the foregoing as my invention, I have signed my name this 27 day of Feb., 1925.

ISIDORE BUCHMAN.
